UNITED STATES PATENT OFFICE.

HERBERT C. LONG, OF SAN FRANCISCO, CALIFORNIA.

DESIGN FOR A SIRUP CAN.

Application filed June 9, 1924. Serial No. 9,838. Term of patent 14 years.

To all whom it may concern:

Be it known that I, HERBERT C. LONG, a citizen of the United States, residing at San Francisco, in the county of San Francisco and State of California, have invented a new, original, and ornamental Design for a Sirup Can, of which the following is a specification, reference being had to the accompanying drawing, forming part thereof.

Fig. 1 is a side elevation; Fig. 2, is a rear elevation and Fig. 3, is a front elevation of a sirup can, showing my new design.

I claim:

The ornamental design for a sirup can, as shown.

HERBERT C. LONG.
